UNITED STATES PATENT OFFICE.

ALBERT J. RYAN, OF CINCINNATI, OHIO.

PROCESS OF FORMING BOX TOES FOR SHOES.

Application filed January 15, 1920. Serial No. 351,666.

To all whom it may concern:

Be it known that I, ALBERT J. RYAN, a citizen of the United States, and a resident of the city of Cincinnati, in the county of 5 Hamilton and State of Ohio, have invented certain new and useful Improvements in a Process of Forming Box Toes for Shoes, of which the following is a full, clear, and exact description, reference being had to the drawings forming a part of this specification.

My invention relates to processes and the products thereof involved in the formation of stiffened toe pieces for shoes. The nature of the material employed is subject to a wide 15 range of selection, but the customary and preferred material is a felt body impregnated with waxes and gums.

It is the object of my invention to provide a method of forming box toes for shoes prior 20 to their insertion in the shoe, and to provide by my method a box toe which is superior to any like toes of the past, and possessed of different characteristics, among which are a thinner and stiffer body, and cleaner lines 25 around the folded edges.

One of the essentials of my invention is that I take a box toe piece of the desired material, impregnated with a softened and plastic medium, and by a separate treatment 30 apart from any other portions of the shoe, stretch the material over a form having special characteristics. I maintain the piece over the form until it has set by hardening or partial hardening and due to the features 35 of the form, and the method of "striking up" the piece over the form I obtain the advantageous product noted briefly above, and which will be hereinafter specifically pointed out and claimed, together with the 40 details of the method employed.

In the drawings,

Figure 1 is a perspective view of one selected form of holder for a box toe piece.

Figures 2, 3 and 4 are views showing the 45 formation of the toe piece into the desired shape, with phantom machine parts, more or less diagrammatically indicated.

Figure 5 is a perspective view of a completed box toe piece.

Figure 6 is a sectional perspective of the 50 toe of the forming die or "toe last" which is employed by me.

In the past few years, the method of making up box toes has chiefly been to insert 55 a plastic toe piece together with the upper

on a last, and proceed to last the shoe, while the piece is soft, after which the shoe is set aside to permit the toe to harden.

Since the toe piece is formed over the shoe last along with the parts of the upper 60 and its lining there is no possibility of giving any special treatment to the box toe piece itself, because any stretching or molding of the piece is limited by the stretchability or moldability of the upper material. Not only this but the operation of 65 lasting, as it is done today, is largely required because of the necessity of working the box toe piece into the required form; and by the forming up of the said toe piece 70 into the exact desired shape before its insertion into the shoe, the operation of lasting is done away with almost entirely.

The elimination of the necessity of treating a plastic piece of material along with 75 the other parts of the shoe, is also a saving because of the fact that the operator is relieved of the danger of ruining the exposed portions of the shoe with the chemicals, 80 gums, waxes, or the like, which provide the plasticity of the piece.

According to my invention, therefore, the box toe piece is formed up into the exact shape desired for the completed shoe, prior 85 to its being incorporated with the balance of the shoe on the last. Not only this, but being relieved of the necessity of operating on the upper along with the plastic piece, I am enabled to stretch or attenuate the 90 piece itself, resulting in a more desirable product both from the point of view of neatness, and of hardness.

I employ in my process, a "toe last" or former of which the toe portion 1 is shaped in the form of the toe of the shoe last to 95 which the completed piece is to be applied, and which has a U-shaped channel 2 directly beneath the edges of the said toe portion, there being enough excess depth to the form to provide a toe which is slightly 100 greater in depth or altitude than the toe of the ultimate shoe last. This is because the toe piece when formed must conform to the shoe last toe with an insole superimposed at its underside thereof.

I have shown as a practical form of 105 holder for the toe piece itself, a device which has two plates 3, 3, hinged together by spring hinges 4, 4, the two plates having handles 5, 5. The plates are cut out at the 110

forward end to form jaws 3^a and the box toe blank 6 is inserted between the jaws so that the wide end thereof lies practically flush with the end of the plates, as shown 5 in the dotted line illustration in Figure 1. An additional spring 5^a may be placed between the handles.

The toe last, or former, being properly retained and balanced so as to receive an 10 even application of the toe piece, I preferably insert the holding device containing a plastic toe piece over the said last, and initially retain the said piece against the top of the last by a resilient member 7.

15 I then press down on the holding device around the edges of the jaws, so as to retain the box toe piece firmly against substantial withdrawal, employing, for example, a series of depressible posts 8. I 20 also preferably support the holder on a table 9 which is depressible but only upon the application of considerable force.

By moving the toe piece downwardly over the toe form, while retaining the edges of 25 the piece as by depressing the posts, I attenuate the body of the plastic piece, and shape it to the toe former, except at the channel which directly underlies it.

To provide for the channel I preferably 30 provide a flexible member such as indicated at 10, which, after the piece has been stretched down over the toe form or last, will come into action to force the piece to enter the channel and conform thereto.

35 Having brought the piece down over the form, and stretched it at the same time, it should be held in such position until it has fully set. By this I do not necessarily mean, completely hardened but that it 40 should be in such condition that it may be removed and set aside, without losing the shape and attenuation, that was imparted to it over the former or last. Preferably, and due to the great economy of so doing, a box 45 toe piece which is impregnated with a hardening compound that hardens very quickly, after being softened, and has a very high heat resistance when hard, will be used in my process. Thus I employ among other 50 things a felt impregnated with waxes and gums which will soften in dry heat, hot water, or steam and will harden very quickly.

55 As a result of this forming process which, of course, might be beneficially followed, with the use of other instrumentalities, the completed box toe piece will have an attenuated or stretched body 11, a clean sharp line at the turned under edges 12, and a clearly defined depending flange or shoulder 13. As shown in the drawings, the excess material 14 around the edges of the complete article will naturally be thicker than the balance of the article. The showing is exaggerated to bring out the variance in

thickness, and the stretching will vary due to the firmness with which the edges are held during the action on the blank.

Any desired form of knife may be used to cut away the excess material, which will 70 preferably be done along the base of the depending flange or shoulder 13, unless, as for McKay shoes, the inwardly extending portion beneath the toe is all that is needed, in which case the cutting is done along the 75 upper edge of the shoulder 13.

In placing the toe into a shoe, the insole, and upper are assembled on the last in the usual way, with the box toe inserted between the upper and its lining. The shoulder 13, will then lie along the upturned lip 80 of the insole (for welt shoes) and the in-seamer can stitch the upper, and toe, to the insole lip, employing the said shoulder as a body to stitch to, for the toe piece. 85

The operation of lasting the shoe, as done at present, will not be required, as the toe piece is already in form, and will hold its shape.

It is not intended by the failure to point 90 out equivalents in the above matter, or the failure to describe the various kinds of materials which are available for box toes, and the nature of the hardening compounds, to imply limitations in the claims that follow. Nor is it intended that the scope of 95 my invention be limited to the exact purpose set forth above, since I intend it to be applied wherever the teaching thereof may be made available, now, or in the 100 future.

Having thus described my invention, what I claim as new and desire to secure by Letters Patent is:—

1. A method of preparing box toes for 105 shoes which consists in independently forming a plastic blank over a forming die having the shape of the desired toe and an underlying channel with a base and side walls, and retaining said blank over said die and 110 in said channel until in a state of fixation.

2. A method of preparing box toes for 115 shoes which consists in independently stretching and attenuating a plastic blank over a forming die, having the shape of the desired toe, and retaining said blank in stretched and attenuated condition over the 120 said die until in a state of fixation.

3. A method of preparing box toes for 120 shoes which consists in rendering plastic a blank of impregnated felt material, and stretching and attenuating it over a toe die of the desired shape, and retaining it in stretched and attenuated relation until in 125 a state of fixation.

4. A method of forming box toes adapted 130 for assembly together with the upper in a shoe, which consists in striking up over a former a toe portion conforming to a given

last from a flat piece of elastic material having hardening properties, the said flat piece having an approximate toe outline, and firmly holding the margins of the piece 5 entirely around the piece, except at the back so as to impart a stretching operation over the former.

5. A method of forming box toes adapted for assembly together with the upper in a 10 shoe, which consists in elastically shaping a flat piece of material to a member conforming to the toe portion of a given last and holding said piece momentarily in stretched and attenuated conformation to the former 15 to initially set the components of the material in complete box toe formation.

6. A method of forming box toes adapted for assembly in the lasting of a shoe, which consists in cutting out a toe blank from a 20 flat piece of fabric having elastic and self-hardening components, simultaneously firmly holding the margins of the flat toe blank entirely around the piece except at the back while elastically distorting said 25 flat piece and shaping it to conform to the contour of the toe portion of a given last, and holding the stretched material momentarily to initially set the components of the material in complete box toe formation in a 30 single operation.

7. A method of forming box toes adapted for assembly in the lasting of a shoe, which consists in firmly holding the margins of a 35 flat toe blank of a fabric having elastic and cold-hardening components entirely around the piece except at the back and while said blank is in a heated condition shaping it under pressure to a die member conforming in size and contour to the toe portion of a 40 given last, and drawing in a marginal portion of the blank below the toe so as to form an offset shoulder adapted for attachment to the lip of an insole.

8. A method of forming a box toe adapted for assembly in the lasting of a shoe 45 which consists in firmly holding the margins of a flat toe blank of a fabric having elastic and cold-hardening components entirely around the piece except at the back 50 and while said blank is in a heated condi-

tion shaping it under pressure to a die member conforming in size and contour to the said toe portion of a given last, and holding the stretched material momentarily to initially set the components of the material in 55 complete box toe formation.

9. As a new article of manufacture, adapted for assembly together with the upper in a shoe, a box toe pre-formed on a die corresponding to the toe portion of a given 60 last, from an elastic, self-hardening material, and characterized by the fixation of the material in a condition of stretched and attenuated conformation to the die.

10. A box toe adapted for assembly together with the upper in a shoe and consisting of a shell-like structure of felt material, the components of which are set in an independently stretched and attenuated state of 65 conformity to the toe of a given last.

11. A box toe adapted for assembly together with the upper in a shoe, formed of an independently stretched, attenuated and fixed felt material, having a member for attachment to the lip of the insole.

12. A box toe for assembly together with the upper in a shoe, formed from a flat elastic material independently stretched and attenuated to a pre-determined toe contour, the components of which are in a condition 80 of substantial fixation.

13. The method of forming a box toe, which consists in uniformly holding the margins of a flat blank of appropriate outline formed of an elastic and cold-hardening material adapted to stitching, striking up a toe form from a medial portion of the gripped blank, and holding the form momentarily in stretched and attenuated condition for hardening.

14. A box toe for assembly, together with the upper of a shoe, consisting of a crisp tenuous elastic material, having the desired toe form and dimensions, and a base margin suitable for stitching, said box toe being 95 characterized by a structural attenuation of the material incident to striking up the toe form from a flat blank.

ALBERT J. RYAN.
